Patented Apr. 3, 1917.

2 SHEETS—SHEET 2.

A technical drawing of a rectangular component. It features a central slot with a cross-hatched pattern. At the top and bottom corners of the rectangle, there are circular features. The top circular feature is labeled '16' and the bottom circular feature is labeled '18'.

A technical line drawing of a mechanical assembly. The drawing shows a base structure with various components labeled with numbers 5 through 18. A vertical rod or shaft is positioned in the center, with a cylindrical part labeled 11 at its top. A horizontal plate or bracket labeled 17 is attached to the side of the shaft. A rectangular component labeled 8 is mounted on the side of the shaft. A small rectangular part labeled 10 is attached to the base. A larger rectangular component labeled 12 is attached to the base, and a smaller rectangular part labeled 13 is attached to its side. A curved bracket labeled 14 is attached to the side of the base. The drawing is labeled 'Fig. 5.' in the bottom left corner.

UNITED STATES PATENT OFFICE.

MURL DE WITT, OF MOUNT AYR, IOWA.

RIDING-HARROW.

1,221,152.

Specification of Letters Patent.

Patented Apr. 3, 1917.

Application filed June 25, 1915. Serial No. 36,338.

To all whom it may concern:

Be it known that I, MURL DE WITT, a citizen of the United States, residing at Mount Ayr, in the county of Ringgold and State of Iowa, have invented certain new and useful Improvements in Riding-Harrows, of which the following is a specification.

My invention relates to harrows and more particularly to harrows of the "riding" type.

An object of the invention is to generally improve in the construction of the harrow cart.

15 A further object of the invention is to provide a wheel mounting of novel arrangement whereby inequalities and obstructions in the field-bed may be encountered and successfully passed without deviating the harrow 20 sections from a straight line course of travel.

Generically speaking, the invention may be said to consist in the novel construction, combination and arrangement of parts to be hereinafter more fully described and particularly pointed out in the appended claims.

In the drawings, annexed:

Figure 1 is a plan view of my improved harrow cart;

Fig. 2 is a central longitudinal sectional view;

Fig. 3 is a section on the line 3—3 of Fig. 2; and

Fig. 4 is a detail perspective view of the casting utilized as a support for the harrow 35 wheel.

Referring now to the drawings by numerals, 1—1 designate the harrow sections, each equipped with teeth 2 of suitable size and design. The sections 1 are fastened as indicated at 3 to an evener 4 mounted forwardly of the harrow sections and in such proximity to the ground as to maintain said sections at all times in substantially a horizontal plane.

45 The harrow cart designated as an entirety by the numeral 5 is made up of a frame of novel design or formation in that the forward end thereof extends at an angle to the vertical that the evener may be positioned as before pointed out. The mentioned frame is preferably constructed from a single casting, the sides of which extend in parallelism at the tail end of the harrow and in divergent relation at the forward end

thereof. A cross beam 6 acts as a brace for 55 the frame as do the beam 7 and the platform 8.

The platform 8 is enlarged at a point intermediate its ends or as indicated at 9 and provided with the vertical bore 10 within 60 which the shank 11 of the wheel casting 12 is fitted. Casting 12, as shown to advantage in Fig. 4 is of an inverted U-shaped formation in that the arms thereof extend in parallelism and afford a support for an axle 13 65 upon which the wheel 14 of the harrow is mounted.

The under side of the enlargement 9 is disposed in such relation to the casting 12 as to rest on the top face of the connecting 70 portion thereof. If desired, a washer 15 may be interposed between said connecting portion and said enlargement.

The shank 11 is exteriorly threaded at its free end or as indicated at 16 to receive a 75 nut 17, which nut, as will appear herein-after acts as a retaining means whereby an equalizer rod or arm 18 is held in place. The shank 11 penetrates the said equalizer rod at a point equi-distant from its ends to 80 in this manner serve as a pivot support therefor.

Arm 18 extends transversely of the frame in a substantially horizontal plane and is connected with the brace beam 6 through the 85 medium of rods 19 and springs 20. That a direct pull may be exerted on the terminals of the mentioned arm, the rods 19 cross one another as shown in Fig. 1.

The seat 21 for the operator is affixed as 90 at 22 to the platform 8 and positioned almost directly over the wheel 14 that the weight of the operator may be borne solely by said wheel and not by the harrow sections 1.

In practice, and assuming that the wheel 95 14 has come in contact with an obstruction in the field-bed, it is apparent that the cart 5 may move laterally without causing the harrow sections 1 to move therewith. The moment the wheel 14 contacts with such obstruction, said wheel is swung at an angle to its supporting frame and against tension of the springs 20 connected to the arm 18. The moment the wheel shall have passed the obstruction, springs 20, by reason of their 100 105 equalizing effect, will return the wheel to its normal position or to the position indicated in Figs. 2 and 3.

From the foregoing, taken in connection with the accompanying drawings it will be observed that jolts and jars incident to operation will be materially reduced; that the 5 supporting wheel may move at an angle to the frame when its direct forward movement is impeded only to be returned to its normal position, the moment the obstruction shall have been passed; and that by extending 10 the springs 20 at the angle shown, a greater and more direct pull upon the arm 18 is obtained.

Having thus fully described my invention what I claim as new and desire to secure by 15 Letters Patent is:—

1. In a harrow cart, a frame including side longitudinal members, spaced transversely at their forward ends and connected by a frame bar, said side members converging 20 rearwardly and provided at the rear portion with a supporting wheel mounted upon a vertical shaft whereby rotation of the wheel about horizontal and vertical axes is provided, resilient elements for resisting 25 the rotation of said shaft in either direction, and harrow elements disposed beneath the frame and connected to said forward transverse frame bar.

2. In a harrow cart, a frame including 30 longitudinal side members spaced at their forward extremities and connected by a transverse frame bar, said side members converging rearwardly and provided at said rearward portions with a supporting wheel 35 mounted in a bracket, having a vertical axis journaled in the frame, whereby said wheel may rotate about horizontal and vertical axes, a transversely extending bar connected at its intermediate portion to the shaft, cross 40 springs secured at their forward ends to a rigid portion of the frame, and at their lower rear ends to the extremities of the bar, whereby rotation of said wheel in a horizontal plane is resisted in either direction, 45 and harrow frames disposed beneath the

frame, and connected to the forward transverse bar.

3. In a harrow cart, a frame including longitudinal side members, spaced at their forward ends and connected by a transverse frame bar, said side members converging rearwardly and formed with rearwardly extending parallel portions connected at their extremities with a transverse frame bar, transverse struts connecting the parallel members, a longitudinal casting connecting the rear transverse bar and one of the transverse struts having a bearing portion to receive a vertical shaft, an inverted U-shaped bracket supported at the lower end of the shaft, a supporting wheel mounted for rotation in said U-shaped bracket, a transverse arm connected at its intermediate portion to the upper end of the shaft, coil springs connected to the extremities of the arms, extending forwardly in crossed relation, and connected to a rigid portion of the frame, and harrow frames disposed beneath the main frame connected to the forward transverse bar.

4. In a harrow cart, a frame, a casting comprising a shank journaled in a bearing therefor rigid with the frame and an inverted U-shaped member mounted for turning movement relatively to the frame, a 75 supporting wheel carried by said member, an equalizer arm rigid with the shank, and means including transversely disposed springs mounted to engage with the respective arm terminals and with the frame to 80 yieldingly maintain said casting and the wheel carried thereby against movement in the manner stated.

In testimony whereof I affix my signature in presence of two witnesses.

MURL DE WITT.
